UNITED STATES PATENT OFFICE.

HENRY WOLF, OF WEST HOBOKEN, NEW JERSEY.

CORNER-PIECE FOR WINDOWS.

1,224,988.

Specification of Letters Patent.

Patented May 8, 1917.

Application filed April 20, 1916. Serial No. 92,470.

To all whom it may concern:

Be it known that I, HENRY WOLF, a citizen of the United States, residing at West Hoboken, in the county of Hudson and 5 State of New Jersey, have invented new and useful Improvements in Corner-Pieces for Windows, of which the following is a specification.

An object of the invention is to produce 10 a device of this character which shall be of an extremely simple construction, cheap to manufacture and which may be easily and quickly applied.

Other objects of the invention are to produce 15 a corner piece for window sashes that will materially strengthen the sash at the joints or corners thereof; to prolong the life of the sash by preventing the accumulation of moisture in the corners of the sash; to 20 facilitate the cleaning of the glass and sash and to prevent the accumulation of dirt at the corners of the sash and also to assist in maintaining the glass in proper position upon the sash.

25 The foregoing objects, and others, are accomplished by the construction and arrangement of the corner pieces constructed in accordance with my invention and a satisfactory embodiment of which is illustrated by 30 the accompanying drawing.

In the said drawing:

Figure 1 is a perspective view illustrating the application of my improvement,

Fig. 2 is a sectional view approximately 35 on the line 2—2 of Fig. 1,

Fig. 3 is a sectional view approximately on the line 3—3 of Fig. 1,

Fig. 4 is a perspective view of a corner piece constructed in accordance with the 40 present invention,

Fig. 5 is a similar view of a modification, and

Fig. 6 is a view of the blank from which the corner piece is formed.

45 Referring now to the drawing in detail 1 designates an ordinary window sash having the usual panes of glass which are held thereon by putty 3 in the usual manner.

In accordance with my invention each 50 pane of glass is provided with a corner piece 4, and as illustrated in Fig. 6 of the

drawing each of these corner pieces is struck from a single piece of suitable, preferably resilient metal.

The corner pieces 4 each include a curved 55 body 5 that has one of its edges provided with an angularly disposed prong 6 and its opposite edge provided with an extension projecting in the direction of the prong and providing what I will term an apron 7. 60

The body 1 is disposed to straddle the putty 3 and the prong is forced into the sash and into contact with the glass, while the apron 7 is arranged to engage with the outer surface of the sash and to be secured 65 thereto in any desired or preferred manner, such for instance, as through the medium of a headed brad 8.

The structure disclosed in Fig. 5 of the drawing is substantially similar to that just 70 described, but this device, indicated for distinction by the numeral 9, is adapted for use in the corners of comparatively small sashes, such, for instance, as are employed in railway cars or the like, but the said 75 structure may be also employed, and as illustrated in the drawing, at the corners of the reduced center stiles of the ordinary sashes.

From the above description, taken in connection with the accompanying drawing, 80 the simplicity of the device, as well as the advantages thereof will, it is thought, be perfectly apparent to those skilled in the art to which such invention appertains without further detailed description. 85

Having thus described the invention, what I claim is:

1. The combination with a window sash, a glass fitted thereto, and means for securing said glass to said sash, of corner pieces, 90 each including a body having an inner prong and an outer apron, each of said corner pieces disposed to straddle the glass securing means and to have its prong enter the sash and contact with the glass and its 95 apron to engage with the outer surface of the sash and to be secured thereto.

2. The combination with a window sash, a glass fitted thereto, and means for securing said glass to said sash, of resilient corner pieces for said sash, each of said corner pieces including a rounded body having one 100

of its edges formed with an angularly extending prong and its outer edge formed with an apron extending from the body in the direction of the prong, said corner piece
5 arranged to straddle the glass securing means at the corners of the sash and to have its prong forced in the sash into contact with the glass and its apron to engage

with the outer surface of the sash, and means for securing the apron to the sash.

10

In testimony whereof I affix my signature in presence of two witnesses.

HENRY WOLF.
